UNITED STATES PATENT OFFICE.

JAMES V. COLLINS, OF GEORGETOWN, DISTRICT OF COLUMBIA.

IMPROVEMENT IN FLOATING-DERRICKS.

Specification forming part of Letters Patent No. 42,561, dated May 3, 1864

To all whom it may concern:

Be it known that I, JAMES V. COLLINS, of Georgetown, in the District of Columbia, have invented a new and Improved Floating-Derrick; and I do hereby declare the following to be a full and exact description of the same, reference being had to the accompanying drawings, making part of this specification, in which—

Figure 1 is a horizontal section of my improved derrick, illustrating the floats or hulls to be hereinafter described. Fig. 2 is a plan of the upper bracing. Fig. 3 is a vertical longitudinal section in the line E F, Fig. 1. Fig. 4 is a vertical transverse section in the line G H, Fig. 1.

Similar letters of reference indicate corresponding parts in the several figures.

This invention relates to a floating contrivance of great strength, and adapted by its peculiar construction to raise sunken vessels and other submerged bodies of immense weight, without the possibility of failure. The apparatus may also be employed for transferring ordnance or other weighty bodies, as will be hereinafter explained.

In order that others skilled in the art to which my invention appertains may be enabled to fully understand and use the same, I will proceed to describe its construction and operation.

In the accompanying drawings, I J represent two hulls or floats which occupy parallel positions and which may be of any suitable size and capacity. From each of these floats rise a series of derricks or standards, A A A, securely supported and braced at their lower ends, as shown in the drawings. The hulls I J are connected together so as to move simultaneously and in conformity with each other by arches, C C, which may be either formed of wood and strengthened with iron P, or they may be formed entirely of iron. These arches C C are secured to and near the bases of the derricks A, in the manner shown, and their curvatures are to be sufficient to allow a vessel of any dimensions to be raised up between the floats I J, the height of the said arches being from forty to fifty feet, (more or less,) according as circumstances may dictate. The arches are each formed in two parallel disjointed sections, C C, respectively,

between which the tackle l may pass and by which the same may have steadiness imparted to it while the sunken vessel or other submerged body is in course of elevation.

The tops of the derricks A are tied or connected by cross-pieces E, which may also be either formed of wood and strengthened with iron n, or entirely composed of the latter. The derricks are securely braced by strong truss-frames D, which are counterbraced by the pieces d d. The whole are further secured together and strengthened by the rods i i m.

In the accompanying illustration of my invention, two grappling or elevating hooks, x x, and two sets of tackle, l, are represented as being employed in connection with each of the arches C C. Each tackle works over a pulley, k, secured in and near the upper ends of the respective derricks A through an aperture in the truss-frames D D and over pulleys j j, suspended from said truss-frames D, as clearly shown in Fig. 4 of the drawings.

L may represent crabs or compound windlasses for operating the tackle, to which crabs either hand, steam, or other power may be applied. If steam be employed it may be readily supplied from an engine or engines located on one or both of the hulls I J.

The above-described contrivance may be built quickly and at little cost and affords a lifting mechanism whereby vessels of the greatest dimensions or weight can be elevated without difficulty, and by means of the hulls or floats a vessel when elevated may be sustained for any length of time or conveyed to a dock or other place of safety. The apparatus may also be employed to advantage for many other useful purposes—such, for instance, as lightening vessels over shallow places, removing obstructions, drawing piles, or conveying from place to place ordnance or other heavy bodies, which may be suspended between the hulls or floats I J by the hooks x x, the crabs L being locked by any suitable device.

The parts are so connected that the entire frame-work may be taken to pieces and placed on one or both the hulls or boats I J to facilitate transportation.

Having thus described my invention, the following is what I claim as new therein, and desire to secure by Letters Patent:

1. In combination with the hulls or floats

J, the abutments A A and connecting arches C C, constructed and arranged substantially as herein shown and described.

2. The derricks A, in combination with the truss-frames D D and brace-rods or ties $i i' m$, the whole being constructed and arranged in the manner and for the purpose set forth.

3. In combination with the above parts, the

tackle l and grappling-hooks $x x'$, arranged and operating substantially in the manner described.

JAMES V. COLLINS.
